UNITED STATES PATENT OFFICE.

ADONIRAM J. WILSON, OF PORT CHESTER, NEW YORK, ASSIGNOR TO THE
HALL SIGNAL COMPANY, OF MAINE.

ELECTRIC RAILWAY-SIGNAL.

SPECIFICATION forming part of Letters Patent No. 470,813, dated March 15, 1892.

Application filed November 9, 1891. Serial No. 411,293. (No model.)

To all whom it may concern:

Be it known that I, ADONIRAM J. WILSON, a citizen of the United States, residing at Port Chester, Westchester county, State of New York, have invented a certain new and useful Improvement in Electric Railway - Signals, which improvement is fully set forth in the following specification and the accompanying drawings, which form a part hereof.

10 The present invention relates to automatic electric block-signals for railways; and it has for its object to improve and simplify the operation of such systems and to reduce the expense of operating such systems; and it 15 consists of the devices herein shown and claimed.

The accompanying drawings represent, diagrammatically, the invention as applied to a series of blocks on a line of railway, including 20 the first and last blocks of the railway, A being supposed to be the first and G the last block of the railway. The greater number of blocks naturally found on any given installation in practice would be equipped by duplicating indefinitely often the arrangement of 25 circuits and of instruments shown in connection with the intermediate blocks of the series represented—as, for instance, with blocks marked C, D, E, and F. In the installation 30 represented in the drawings the length of track is divided into separate sections, which are insulated from each other in the well-known way and are marked in the drawings A, B, C, D, E, F, and G. The trains are supposed to be moving upon the track in the 35 direction indicated by the arrows. Each track-section has a battery near the end of the same, marked, respectively, A', B', C', D', E', F', and G', and in the familiar way the rails 40 of each section form a part of the circuit of the battery pertaining to that section.

The arrangement of devices will be best explained by describing in order, in connection with the drawings, the successive operations of a train upon those devices in passing 45 over the sections of track represented.

It will be understood that the length of the different sections may be anything desired—as, for instance, a half-mile each—or varying 50 lengths, if desired, at different parts of the

railway, depending upon the frequency of trains, the presence of curves, tunnels, &c.

First operation—on train entering track-section A: If track-sections B and C are clear of trains, the train entering A in the well-known way short-circuits the current of the battery A' from the relay 1, demagnetizing that relay and closing at its armature 2 the signal-circuit of the signal S, the current of battery 3 flowing through said circuit and drawing the signal S to "clear" in the ordinary way. This continues as long as any part of the train remains upon track - section A. If, however, track-section B is occupied by a train, that train on B short-circuits the current of battery B' 55 and demagnetizes relay 4, thus breaking at 5 the signal-circuit of signal S, so that in that case the operation of the train on A to close at 2 the break there in the signal-circuit of signal S does not close all the breaks in that signal-circuit—to wit., does not close the break at 5 caused by the train on track-section B—and so does not draw the signal S to "clear," but leaves it at "danger," on which the engineer of the train on track-section A would stop on 60 section A and before signal S until it cleared. Again, if track-section B is clear of trains, but C is occupied by a train, that train on C short-circuits battery C' and demagnetizes relay 7, thereby breaking at 8 the signal-circuit of signal S, so that in that case, as before, the signal S would not clear before the engineer of the train entering section A, but while the latter train remains on section A, (thus closing at 2 the break there in the signal-circuit 65 of the signal S.) Then the moving of the preceding train from section B (which closes at 5 the break there in the circuit of signal S) and its subsequent moving also from section C (which closes at 8 the last remaining break 70 in the signal-circuit of signal S) operates to clear signal S in the eyes of the engineer of the waiting train on A. He can then proceed, knowing that track-sections B and C must be 75 clear of trains.

Second operation—on train entering track-section B while track-sections C and D are clear of trains: The train short-circuits the current of battery B', demagnetizing relay 4. This breaks the signal-circuit of signal S at 80 85 90 95 100

5, (sending that signal to "danger" and keeping it there, although another train enters A,) and makes the signal-circuit of signal S' through battery 3 at 6, (drawing signal S' to "clear.") If, 5 however, there is a train on section C, it will demagnetize relay 7 and break at 8 the circuit of signal S', so that signal S' will not clear before the engineer of the train entering section B. Similarly, if there is a train 10 on section D that train will demagnetize relay 11, and so will demagnetize relay 12, and so will demagnetize relay 7, thereby breaking at 8, as before, the circuit of signal S', so that that signal will not clear before the train entering B. The passage of the train on section C from that section and from section D closes at 8 the breaks there in the circuit of signal S' and causes that signal to clear before the waiting train on section B. 15

20 Third operation—on train entering track-section C while track-sections D, E, and F are clear of trains: The train short-circuits the current of battery C' and demagnetizes relay 7. This breaks the signal-circuits of signals S and S' at 8 (sending or continuing those signals at "danger") and makes at 9 the circuit through battery 10 of the signal S², (clearing that signal.) If, however, there is a train on section D it demagnetizes relay 11, breaking at 13 the circuit of signal S², so that that signal will not clear before a train on section C. Similarly if there is a train on section E it demagnetizes relay 14, breaking at 15 the circuit of signal S², so that that signal will not clear before the train on section C. Similarly if there is a train on section F it demagnetizes relay 16, which breaks at 17 the circuit of battery 18, demagnetizing relay 19, which breaks at 20 the circuit of battery E', 25 which breaks at 20 the circuit of battery E', 40 demagnetizing relay 14, which, as before, breaks at 15 the circuit of signal S², so that that signal will not clear before the train which is on section C; but when the train on section D leaves that section, thereby closing the break at 13, and also leaves sections E and F, thereby closing the break at 15, then the signal S² will clear before the train waiting on section C.

45 Fourth operation—on train entering track-section D while sections E and F are clear of trains: The train short-circuits the battery D', demagnetizing relay 11. This breaks at 21 the circuit of battery 22, which demagnetizes relay 12, which breaks at 23 the circuit of battery C', which demagnetizes relay 7, which breaks at 8 the circuit of signal S', thus continuing that signal at "danger." The demagnetizing of 11 also breaks at 13 the circuit of signal S², throwing it to "danger." It 55 also closes the breaks at 24 and at 9 in the signal-circuit of signal S³, (the latter by demagnetizing relay 7, as above,) thus clearing the signal S³. If, however, there is a train on section E, it demagnetizes relay 14 and breaks 60 at 15 the circuit of signal S³, and so that signal cannot clear; and if there is a train on

section F it demagnetizes relay 16 and by the break at 17 demagnetizes relay 19 and by the break at 20 demagnetizes relay 14, and so, also, breaks at 15 the circuit of signal S³, and so that signal cannot clear; but when the train passes from sections E and F then the break at 15 is closed, and the signal S³ clears before the waiting train on section D.

70 Fifth operation—on train entering track-section E while sections F and G are clear of trains: The train demagnetizes relay 14. This cuts off at 15 the current of battery 10 from signals S² and S³, continuing them at or sending them to "danger." It also closes at 25 the break there in the signal-circuit of signal S⁴, the current of battery 26 thereupon clearing that signal before the train. If, however, there is a train on section F, it demagnetizes relay 16 and breaks at 27 the circuit of signal S⁴, thus preventing 85 that signal from clearing before the train entering section E. Similarly, if there is a train on section G it demagnetizes relay 28 and so breaks at 29 the signal-circuit of signal S⁴, thus preventing 90 that signal from clearing before a train moving on section E; but when the train passes from section F, thus closing the circuit of signal S⁴ at 27 and also passes from section G, thus closing that same circuit at 29, the signal S⁴ clears, and the train on section E is at 95 liberty to proceed.

100 Sixth operation—on train entering track-section F while track-section G is clear of trains: The train on F demagnetizes relay 16. This breaks at 27 the circuit of signal S⁴ and throws that signal to "danger." It also breaks at 17 the circuit of battery 18, demagnetizing relay 19, breaking at 20 the circuit of battery E' and demagnetizing relay 14, which 105 breaks at 15 the circuits of signals S² and S³ and continues them at "danger." The demagnetizing of relay 16 also closes at 30 and 25 (the latter through the demagnetizing of relay 14) the signal-circuit of signal S⁵, and thus clears that signal. If, however, there is a train on track-section G, it demagnetizes relay 28, breaking at 29 the circuit of signal S⁵, and so preventing that signal from clearing 110 before the train moving on section F. When the train passes from section G, it will close the signal-circuit at 29 and the signal S⁵ will clear.

115 In the particular arrangement of signals and signal-circuits shown in the drawings, 120 which is the preferred arrangement, it is intended that each alternate signal S S² S⁴ shall be merely a green or cautionary signal, which the engineer is supposed to pass even while it is set at "danger," but to pass with 125 a precautionary notice to look out sharply for the next signal, and that the intervening signals S' S³ S⁵ should be absolute signals, which the engineer is supposed never to pass except when they stand at "clear." The advantages of such cautionary signals are many. 130 It will be observed that the cautionary sig-

nal S^2 cannot clear in front of a train entering track-section C unless track-sections D, E, and F are clear of trains, whereas the absolute signal S^3 will clear in front of a train entering track-section D if E and F are free of trains, so that an engineer seeing the cautionary signal S^2 clear before him knows that the absolute signal S^3 will also clear before him. On the other hand, the engineer having passed signal S' at "clear" (which shows that sections C and D are clear of trains) and finding cautionary signal S^2 at "danger" and failing to clear before him, knows that S^2 is at "danger," not because of a train on section D, but because of a train on section E or F, and so he runs by signal S^2 , but is on the look out for "danger" at signal S^3 , for that signal S^3 will not clear before him unless the preceding train has left both E and F, and if that signal does not clear before him he stops his train on section D until it does clear.

It is not essential to the main invention, however, that the intermediate signals should be employed as cautionary signals or be affected by the action of the train on the second or third succeeding rail-circuits, and in such event the connecting circuits and circuit-breakers affecting that end would be omitted.

It will thus be observed that in the broad invention the rail-circuits are normally closed and the signaling-circuits—the circuits directly operating each signal—are normally open or broken, being normally open or broken at a circuit-closer which is constructed to be closed by the action of the train upon one of the rail-circuits—the one at or near the end of which the signal operated by that signaling-circuit stands—and that the signaling-circuit is also capable of being broken by one or more normally-closed circuit-breakers which are constructed to be opened by the action of a train on one or more of the next succeeding rail-circuits of the line. It will also be observed that in the invention as embodied in its preferred form the rail-circuits are, as before, normally closed and the signaling-circuits normally open and open as before at a circuit-closer which is constructed to be closed by the action of a train upon one of the rail-circuits, and that the signaling-circuit is also capable of being broken by normally-closed circuit-breakers which are constructed to be opened by the action of a train on either of the next two succeeding rail-circuits of the line, the alternate signaling-circuits having circuit-breakers constructed to be opened by the action of a train on either

of the next three succeeding rail-circuits of the line.

It will be understood that the visible signals S S' S^2 , &c., may be replaced by audible signals, or by both audible and visible signals, without departing from my invention; also, that the said signals may be replaced by electric locks or interlocking devices, as parts of a larger system, without departing from my invention; also, that said signals, &c., may be operated either directly by the current flowing in the signaling-circuits of the invention or indirectly by those currents—as, for instance, the signals may be directly operated by steam or pneumatic power or by the current of a dynamo or a storage-battery or other source of current, and said power be directed and controlled by the current flowing in the signaling-circuits of the invention without departing from my invention; and it is understood that the construction of the relays and of the signals themselves and their operating mechanisms may be greatly varied without departing from my invention.

What I claim as new, and desire to secure by Letters Patent, is—

1. In a block signaling apparatus, the combination, with a series of normally-closed rail-circuits, of a series of normally open or broken signaling-circuits, each signaling-circuit including a normally-open circuit-closer constructed to be closed by the action of the train upon one of the rail-circuits and also including a normally-closed circuit-breaker constructed to be opened by the action of the train upon the next succeeding rail-circuit of the line, substantially as and for the purpose set forth.

2. In a block signaling apparatus, the combination, with a series of normally-closed rail-circuits, of a series of normally open or broken signaling-circuits, each signaling-circuit including a normally-open circuit-closer constructed to be closed by the action of the train upon one of the rail-circuits and also including normally-closed circuit-breakers constructed on each alternate signaling-circuit to be opened by the action of the train upon the two next succeeding rail-circuits of the line and on the intermediate signaling-circuits to be opened also by the action of the train on the third succeeding rail-circuit of the line, substantially as and for the purpose set forth.

ADONIRAM J. WILSON.
